UNITED STATES PATENT OFFICE.

EDWARD W. NEWELL, OF PITTSBURGH, PENNSYLVANIA, ASSIGNEE TO THE
WESTINGHOUSE AIR BRAKE COMPANY, OF WILMERDING, PENNSYLVANIA, A
CORPORATION OF PENNSYLVANIA.

ORDNANCE-PROJECTILE.

1,309,772.

Specification of Letters Patent. Patented July 15, 1919.

Application filed July 3, 1917. Serial No. 178,353.

To all whom it may concern:

Be it known that I, EDWARD W. NEWELL, a citizen of the United States, residing at Pittsburgh, in the county of Allegheny and State of Pennsylvania, have invented new and useful Improvements in Ordnance-Projectiles, of which the following is a specification.

This invention relates to projectiles and has for its principal object to generate an obnoxious gas within the projectile which escapes upon detonation of the projectile.

In the accompanying drawing; Figure 1 is a central longitudinal section of a projectile embodying my invention, showing the primer in its operative position; and Fig. 2 a similar view of the nose portion of the projectile, with the primer in its non-operating position.

While my invention may be employed in connection with a time fuse controlled projectile, the same is illustrated in the drawing as applied to a projectile adapted to be detonated by impact.

As shown, the projectile may comprise a section of tubing 1 adapted to be attached by screw threads to the base portion 2 and having screw threaded engagement at the front end with a member 3. The nose portion 4 of the projectile is screwed onto the member 3 and a cap member 5 is screwed into said nose portion 4.

Mounted within the member 3 and adapted for longitudinal movement is a firing plunger 6 having a forwardly extending hammer portion 7 and a rearwardly extending cup portion 8 adapted to contain a cartridge 9 formed of a material suitable for forming an obnoxious gas when ignited.

Forwardly of and in alinement with the hammer portion 7, a primer holder 10 containing a primer 11 is mounted in the nose portion 4.

In operation, with the parts positioned as shown in Fig. 1 of the drawing, when the projectile is fired and strikes an object, inertia causes the continued movement of the firing plunger 8 relative to the projectile, causing the spring ring 18 to expand and permit the outward movement of the plunger, so that the hammer 7 strikes the primer 11 and the flame from the primer then passes through a central aperture 12 in

the hammer 7 to a central aperture in the cartridge 9, igniting the cartridge to produce gas.

To facilitate the quick combustion of the cartridge, openings 13 may also be provided in the member 6, and the rear end of the primer holder is slotted, so that the flame from the ignited primer 11 can readily pass through the holes 13 to the cartridge.

The flame from the primer also passes through the opening in the cartridge 9 to the usual tube 14 leading to the projectile explosive charge 15 and since the flame must pass the cartridge and ignite same before the flame reaches the explosive charge, it will be seen that the gas is sure to be produced before the projectile is detonated.

In order to provide for the prevention of accidental explosion of the projectile in handling, etc., the primer holder 10 may be made reversible, so that when transported, the primer holder is placed as shown in Fig. 2 of the drawing, with a knob 16 adapted to take the blow of the firing hammer 7 in case of accidental forward movement of same.

In order to indicate that the projectile is in an inoperative position, a projecting washer 17 may be interposed between the cap 5 and the nose portion 4 when the parts are screwed together.

When it is desired to put the projectile in operating condition, the cap 5 is unscrewed, the primer holder is turned around, so that the primer side is presented to the firing plunger as shown in Fig. 1, the washer 17 is removed, and finally the cap 5 is screwed back into position.

Shells containing obnoxious gases have of course been heretofore employed, but so far as I am aware, the shells were filled with gas under pressure from tanks before firing. This necessitated the transportation of cumbersome apparatus to the front.

According to my invention, the gas being generated within the projectile at or before detonation, does away with the use of any charging apparatus.

Having now described my invention, what I claim as new and desire to secure by Letters Patent, is:-

1. A projectile comprising a casing, a primer therein, and a firing plunger con-

taining a cartridge formed of a substance adapted upon ignition to generate an obnoxious gas.

2. A projectile comprising a casing containing a primer, an explosive charge, and a firing plunger located between the primer and the explosive charge and carrying a substance adapted upon ignition to

generate an obnoxious gas, said firing plunger being apertured to permit the passage of flame from the primer through said substance to the explosive charge. ¹⁰

In testimony whereof I have hereunto set my hand.

EDWARD W. NEWELL.
